UNITED STATES PATENT OFFICE.

CLINTON W. DICKINSON, OF LA CROSSE, WISCONSIN.

DISK FURROW-OPENER.

1,170,740.

Specification of Letters Patent.

Patented Feb. 8, 1916.

Application filed February 19, 1909. Serial No. 478,957.

To all whom it may concern:

Be it known that I, CLINTON W. DICKINSON, a resident of La Crosse, in the county of La Crosse and State of Wisconsin, have 5 invented certain new and useful Improvements in Disk Furrow-Openers, of which the following is a full, clear, and exact description.

The invention relates to disk furrow-openers.

In seeding-machines it is now common practice to employ furrow-openers consisting essentially of a pair of oppositely disposed disks mounted in angular relation to 15 one another for opening a furrow, these being generally known as "double disk" furrow-openers. In this class of devices each disk is independently journaled in the support, and a desideratum is to provide a bearing structure which is as narrow as possible to leave the greatest possible clearance 20 between the furrow-openers which are usually employed in gangs in a seeding-machine.

One object of the invention is to provide 25 an improved double disk drill in which a narrow bearing-structure may be adopted while affording proper bearing-surfaces for the disks, and this result is accomplished by 30 providing the disks with spindles rotating therewith and which are mounted in the support so that they will receive lateral or axial thrust from each other. By thus mounting the disk-spindles they may be very 35 narrow and yet afford proper bearing whereby the disks will be truly journaled and furthermore, the spindles may be brought into contacting relationship, dispensing with the necessity of clearance between their inner 40 ends. Another resultant advantage of this feature is that the disk spindles rotating in the same direction will have rolling contact and thus avoid friction incident to a non-rotating part for receiving inward 45 thrust thereof. A still further resultant advantage of mounting the disk-spindles so their inner ends will receive thrust from each other, is that the rotation of one disk will aid in rotating the other, if the rotation of one is being unduly retarded in operating in the soil.

The invention also designs to provide an improved manner whereby the disk-spindle

or trunnion may be inserted into the bearing in the support. In accordance with 55 this object of the invention, the spindle is insertible into the bearing from that side at which the disk is disposed and held in the bearing by means fixed to the support on the same side thereof, the disk being connected 60 to the spindle after the latter has been inserted in the bearing. Resultantly, the disks may be conveniently removed for sharpening without removing the bearing-spindles 65 rotating therewith, and the means for securing the spindle in its bearing may be formed to serve as a closure for confining the lubricant in the bearing and need not be removed when the disk is removed.

The invention still further designs to improve the construction of disk furrow-openers and more particularly the devices for journaling them in their supports.

The invention consists in the several novel features hereinafter set forth and more particularly defined by claims at the conclusion 75 hereof.

In the drawings: Figure 1 is a side-elevation of a furrow-opener embodying the invention. Fig. 2 is a section on line 2—2 of 80 Fig. 1. Fig. 3 is a similar view, the disk spindles being shown in elevation. Fig. 4 is a central longitudinal section taken through the boot between the disks. Fig. 5 is a side-elevation of a portion of the support and bearing thereon, the spindle at one side being removed. Fig. 6 is a detail perspective of one of the plates for reducing the side-openings in the bearing. Fig. 7 is a perspective view of the cup-shaped dust-guard. Fig. 8 is a perspective of one of the disk-spindles.

The furrow-opener is usually connected to the frame of a seeding-machine by a drag-bar 11 to which is secured a support or boot 95 12 in which is formed a seed-conduit 13 through which the seed is conducted into the furrow formed by the opener. A disk 14 is disposed at each side of the boot and these disks are journaled at an angle to 100 each other relatively to open a furrow, the disks being mounted so their lower portions will be in contact or close proximity, thence diverging toward the rear to widen the furrow as they are drawn through the soil.

105 Each disk is revolvably connected to the

boot or support 12, the latter being formed with an annular wall 15 which serves as a bearing for the disk-spindle. A spindle or trunnion 16 is provided for each disk and 5 is journaled in the bearing 15 of the support, the spindles being journaled at an angle to one another, corresponding to the angular relation of the disks and are oppositely mounted in said bearing, and the periphery 17 of each spindle 16 fits into the recess or opening in the bearing 15 and the inner face 19 of each spindle is conoidal to form a thrust-surface having a rolling contact with the other spindle, whereby the lateral thrust of one spindle will be received and opposed by the other. Each spindle is formed with a reduced portion 20 which extends through a plate 22 having an opening 23 therein which fits around said reduced 10 portion and which confines the spindle against outward movement in its bearing, by engaging the shoulders 17' at the inner end of the reduced portion 20 of the spindle. Each plate 22 is secured to one of the sides 15 of the support by screws 24. The outer end of each spindle is provided with a reduced terminal 25 which is square in form, or other suitable shape, to extend through a correspondingly shaped opening in the disk, so 20 that the disk and spindle will rotate together. A washer 26 engages the outer face of each disk and is secured to clamp the disk on the spindle by a screw 27. A cup-shaped dirt-guard 28, usually formed of 25 sheet metal, is clamped between the disk and the shoulder 29 of the spindle, and comprises an inturned flange 30 which extends around the periphery of plate 22 and prevents the entry of dirt between the disk and the plate 22 and to the bearing for the 30 spindle.

In practice the soil presses against the lower portions of the outer faces of the disks so that inward thrust or pressure will 45 be exerted on the disk-spindles so that the latter will receive lateral thrust from each other at the contacting line or point below the spindle axes. It also occurs in practice that the seeding-machine is at times driven 50 backwardly so that the lower portions of the disks will be pressed outwardly and to keep these spindles properly positioned in the bearing and prevent them from becoming cramped therein, a wall or abutment 30' 55 is formed on the support and fits between the supported portions of the revolving spindles. Under these abnormal conditions the abutment receives lateral thrust at a point opposite the contacting point of the spindles. Thus the spindles will be at all 60 times truly held in the bearings in such manner that excessive friction will be avoided.

An oil-duct 31 is formed in the support

and communicates at its lower end with the 65 opening or chamber in which the spindles rotate, so that lubrication may be supplied to the inclosed spindles, and the walls of the bearing in which they are journaled. By employing a plate 22 which is secured to 70 the support and through which the reduced spindle portion 20 extends, the side-opening in the bearing is reduced to form a well in which the lubricant will be retained by the 75 plate.

As a result of the construction set forth, each disk is provided with a spindle rotating therewith and these spindles receive lateral thrust from each other which makes it 80 possible to employ an extremely narrow spindle which will suffice to properly sustain the disks and avoid unnecessary friction. Furthermore, the engaging surfaces of the spindles are in rolling contact with each other so that no friction will result 85 from the lateral thrust or stresses received by the spindles. By employing an abutment or wall between the non-contacting portions of the relatively angularly disposed spindles, the studs will at all times 90 be truly confined in the bearing-recess or chamber despite any variation resulting from wear of the parts.

In assembling the device, the spindles are first placed into the bearing 15 from the opposite sides thereof and the plates 22 are then respectively secured to the outer sides of the bearing. The spindles will then be held in the bearing against lateral movement in either direction. The cup-shaped 100 guards 28 and disks 14 will then be placed on the reduced terminal 25 of the spindles respectively and securely clamped between washers 26 and shoulders by screws 27. When it is desired to remove one of the 105 disks for sharpening, or to replace one, it is only necessary to remove the screw 27 when the disk will be free to be withdrawn laterally from the reduced terminal of a spindle. Thus, each disk may be removed 110 without disturbing the spindles or bearing.

As a result of mounting the spindles rotatably in the bearing and securing them against outward movement by means at the outer sides of the bearing, and connecting 115 the disk to the spindle after the latter is held in the bearing, by said means, the disks may be removed for sharpening or replacement without removing the spindles. The improved cup-shaped dirt-guard effectively 120 prevents the entry of dirt to the bearing and prevents it from being clogged. The closure plate extending around a reduced portion of the spindle prevents the escape of lubricant from the bearing. The construction throughout is one which makes it 125 possible to employ narrow elements while affording the necessary bearing-surfaces to

keep the disks in rotating and proper relation.

The invention is not to be understood as restricted to the details set forth, since these 5 may be modified within the scope of the appended claims without departing from the spirit and scope of the invention.

Having thus described the invention, what I claim as new and desire to secure by 10 Letters Patent, is:

1. In a double disk furrow opener, the combination of a support provided with a bearing, a pair of disks disposed at the opposite sides of said support, said disks being 15 angled toward each other and having their edges in contact at one point to cause them to open a single furrow by moving the soil laterally and outwardly away from the outer side of both disks and a pair of spindles for 20 the disks respectively, journaled in the bearing in angular relation to each other and having thrust surfaces which receive lateral thrust from each other independently of the bearing.

25 2. In a double disk furrow opener, the combination of a support provided with a bearing, a pair of disks disposed at the opposite sides of said support, said disks being angled toward each other and having their 30 edges in contact at one point to cause them to open a single furrow by moving the soil laterally and outwardly away from the outer side of both disks, and a pair of spindles for the disks respectively, journaled in the 35 bearing and having conoidal bearing surfaces at their inner ends receiving lateral thrust from each other independently of the bearing.

3. In a double disk furrow opener, the 40 combination of a support provided with a bearing, a pair of disks disposed at opposite sides of said support, said disks being angled toward each other and having their edges in contact at one point to cause them to open 45 a single furrow by moving the soil laterally and outwardly away from the outer side of both disks, and a pair of spindles for the disks respectively, journaled in the bearing in angular relation to each other and having 50 conoidal surfaces at their inner ends engaging and receiving lateral thrust from each other independently of the bearing.

4. In a double disk furrow opener, the 55 combination of a support provided with a bearing, a pair of disks disposed at opposite sides of said support, said disks being angled toward each other and having their edges in contact at one point to cause them to open a single furrow by moving the soil laterally 60 and outwardly away from the outer side of both disks, and a pair of spindles for the disks respectively, journaled in the bearing in angular relation to each other and having conoidal bearing surfaces at their inner ends

in rolling contact with each other and receiving lateral thrust from each other independently of the bearing.

5. In a double disk furrow-opener, the combination of a support provided with a bearing, a pair of disks at the sides of the bearing respectively, and angled toward each so that their lower portions will coöperate to cut a furrow, a pair of spindles for the disks respectively, journaled in the bearing in angular relation to each other and 75 having their inner ends provided with surfaces for receiving lateral thrust from each other, and an abutment between said inner ends.

6. In a double disk furrow-opener, the 80 combination of a support provided with a bearing, a pair of disks at the sides of the bearing respectively, a pair of spindles for the disks respectively, journaled in angular relation to each other in said bearing, and 85 having inner surfaces in rolling contact with one another, and an abutment between said surfaces.

7. In a double disk furrow-opener, the 90 combination of a support provided with a bearing, a pair of disks at the sides of the bearing respectively, a pair of spindles for the disks respectively, journaled in angular relation to each other in said bearing and having conoidal inner surfaces in rolling 95 contact with one another at one side of their centers, and an abutment between said surfaces.

8. In a double disk furrow-opener, the 100 combination of a support provided with a bearing, a pair of oppositely disposed disks, a pair of spindles journaled in said bearing for the disks respectively, and mounted in the bearing to receive lateral thrust from each other, and means at the outer sides of 105 the bearing for holding the spindles in the bearing.

9. In a double disk furrow-opener, the 110 combination of a support provided with a bearing, a pair of oppositely disposed disks, a pair spindles for the disks respectively, journaled in said bearing and mounted in the bearing to receive lateral thrust from each other, said spindles having reduced portions, and plates having openings 115 through which the reduced portions extend, secured to the outer sides of the bearing to hold the spindles in the bearing.

10. In a double disk furrow-opener, the 120 combination of a support provided with a bearing, a pair of oppositely disposed disks, a pair of spindles journaled in the bearing to receive lateral thrust from each other, means at the outer sides of the bearing for holding the spindles in the bearing, and means for 125 removably securing the disks to the outer ends of the spindles.

11. The combination of a support having

a bearing therein which is open at both sides, spindles journaled in the bearing and insertable through said open sides respectively, means at the open sides of the support for holding the spindles in the bearing respectively and secured to the support after the spindles have been inserted, and disks respectively secured to the outer ends of the

spindles, said spindles being mounted in the bearing to receive lateral thrust from each other.

CLINTON W. DICKINSON.
